C. E. PARSONS

FEED MECHANISM FOR BUTTON ATTACHING MACHINES

Filed Aug. 29, 1923

UNITED STATES PATENT OFFICE.

CHARLES E. PARSONS, OF WATERBURY, CONNECTICUT, ASSIGNOR TO SCOVILL MANUFACTURING COMPANY, OF WATERBURY, CONNECTICUT, A CORPORATION OF CONNECTICUT.

FEED MECHANISM FOR BUTTON-ATTACHING MACHINES.

Application filed August 29, 1923. Serial No. 659,997.

To all whom it may concern:

Be it known that I, CHARLES E. PARSONS, a citizen of the United States, residing at Waterbury, in the county of New Haven and State of Connecticut, have invented a certain new and useful Improvement in Feed Mechanism for Button-Attaching Machines, of which the following is a full, clear, and exact description.

10 This invention relates to a feed mechanism for button attaching machines, and is designed particularly for use in connection with machines for attaching tack fastened buttons, and is in the nature of a modification of the invention disclosed in the patent of Augustus H. Cosgrove, No. 1,499,203, dated June 24, 1924.

In operating machines of the type above mentioned, it often happens that defective 20 tacks or slugs are placed in and fed from the hopper of the machine, and these defective tacks or slugs sometimes cause jamming or obstruction of the tack feed mechanism. It is the object of this invention to provide 25 means whereby the feed mechanism, in case it becomes jammed, may be easily and expeditiously cleared of such obstructions and be quickly placed in operative condition again.

30 In the patent above mentioned, a movable part is provided in connection with the tack raceway, this part being adapted to be swung out of tack guiding position, whereby one side of the tack raceway is opened for the 35 removal of imperfect tacks or slugs or other obstructions. In the device of that patent, the tack cutoff is arranged in fixed relation to the tack chute, but I have found that this cutoff may be so modified in construction 40 as to be capable of being mounted upon the movable portion of the raceway and be moved therewith so that when the movable portion is swung out of tack guiding position, the whole of the tack feeding raceway 45 may be unobstructed.

To this end the invention consists in a feed mechanism for button setting machines including a tack raceway having a movable portion adapted to be swung out of tack 50 guiding position, and a tack cutoff carried by said movable portion and movable therewith, as I will proceed now to explain and finally claim.

In the accompanying drawings illustrating the invention, in the several figures of which like parts are similarly designated, Figure 1 is a fragmentary sectional side elevation showing an embodiment of my invention applied to a machine of the type described. Fig. 2 is a front elevation of a portion of the parts shown in Fig. 1. Fig. 3 is a rear elevation of the movable portion of the raceway detached with the tack cutoff carried thereby.

In the drawings I show the machine frame or head 1 carrying a setting plunger 2 and a setting anvil 3, and adjacent to the anvil 3 is a table 4 upon which is mounted a plate 5 carrying a stand 6. This stand 6 is so formed as to provide one portion 7 of a tack raceway 8, and a support 9 for a tack chute 10. The tack raceway 8 is completed by means of a movable member 11 pivoted at 12 to an upright extension 13 of the stand 6 and having at its lower forward end a locking lip 14 formed for engagement with a complementally formed edge 15 on the plate 5. This engagement between the parts 14 and 15 prevents any direct vertical movement of the movable member 11, but permits it to swing upon its pivot 12.

In order to prevent untimely movement of the member 11 upon its pivot 12, I provide a latch member 16 pivoted at 17 upon a stud 18, this latch member being formed 85 for engagement with a notch or recess 19 in the horizontal portion 20 of the movable member 11, and provided with a handle 21 by which it may be readily swung upon its pivot 17. To prevent undesired disengagement of the latch member 16 from the recess 19, I provide a dog 22 which engages with a complemental depression 23 in the plate 5. Proper engagement between the dog and its corresponding depression is assured by 90 means of a spring 24 surrounding the stud 18 and bearing upon the latch member 16.

The upper end of the movable member 11 is formed to provide a cam surface 25 against which bears one end 26 of a stop member 27 pivoted at 28 to the tack chute. This stop member is provided with a stop finger 29 which, when the movable member is swung to the position shown in dotted lines in Fig. 2, will fall across the slot in 100 the tack chute through which the points

or shanks of the tacks extend, and will prevent the tacks in the chute from sliding down same.

All of the parts above described are substantially the same, and operate in substantially the same manner, as the corresponding parts of the device of the patent of Augustus H. Cosgrove mentioned.

Pivoted at 30 to the movable member 11 is a tack cutoff 31 having an extension 32 which normally extends across the raceway 8, and the cutoff is recessed at 33 to form a cavity substantially conforming to the shape of the heads of the tacks fed to it. As will be seen, when the movable portion of the raceway is in the position shown in full lines in Fig. 2, the cutoff lies flat against the bottom of the raceway, so that its recess 33 will engage with the heads of the tacks descending the chute 10. The cutoff is provided with an extension or arm 34 which carries a pin 35 normally engaged by a complementary pin 36 carried by a link 37 connected with an operating lever 38 oscillated by suitable mechanism (not shown) through a shaft 39. The arm 34 is also provided with a handle 40, and the movable member 11 is provided with a similar handle 41, and these handles, in addition to their function as means by which the cutoff and movable member may be conveniently grasped, respectively, serve as means for attachment of the ends of a tension spring 42 which normally retains the cutoff 31 in raceway intercepting position.

It will, of course, be understood that oscillation of the lever 38 causes reciprocation of the link 37 and through the pins 36 and 35 transmits motion to the cutoff about its pivot 30, so that upon each upward movement of the lever 38, the cutoff 31 will be moved to tack releasing position, and upon subsequent downward movement of the lever 38 the spring 42 will return the cutoff to raceway intercepting position. It may be noted here that the cutoff is provided with a lip 43 which, when the cutoff is moved to tack releasing position, will lie across the discharge end 44 of the tack chute and will prevent egress therewith of the tacks therein.

It will thus be seen that the movable member 11 and the cutoff 31 and its spring 42, form a unitary structure movable as such about the pivot 12 when it is desired to clear the raceway 8 of imperfect tacks, slugs and other obstructions, and inasmuch as there is no direct connection between the link 37 and the cutoff, the connection between same being merely one of contact between the pins 35 and 36, nothing needs to be detached or unfastened to permit movement of the member 11 about its pivot 12, except of course that the latch member 46 must first be moved out of the way.

As shown in full lines in the drawing, and in the dotted line position of Fig. 2, the cutoff is at the limit of its raceway intercepting position as allowed by the contact of the pin 35 with the pin 36, but it is possible, when the movable member 11 and with it the cutoff 31 are moved to the position shown in dotted lines in Fig. 2, that the spring 42 may turn the cutoff slightly upon its pivot 30, and in order that this turning may be limited so that the cutoff will not assume an undesired position with respect to the movable member 11, I provide the cutoff with a stop shoulder 45 adapted to abut against the side of the member 11 as shown in light dash and dot lines in the dotted position in Fig. 2.

By the arrangement of the cutoff upon the movable member, whereby the two may turn as a unit about the pivot of the movable member, it will be seen that I am enabled to obtain unobstructed access to the tack raceway, and even to the discharge end 44 of the tack chute, if desired, while at the same time sacrificing none of the effectiveness of the operation of the machine to accomplish this purpose.

I have hereinabove described my invention as applied specifically to a tack feed mechanism, but, it is obvious that it may be equally well applied to mechanism for feeding elements other than tacks, and it will be understood that I do not consider the invention as limited to the particular embodiment herein shown and described, as it is obvious that various changes may be made therein without departing from the spirit of the invention or the scope of the following claims.

What I claim is:

1. In a feed mechanism for button attaching machines, a raceway, a movable member forming a lateral guide for a part of said raceway, and a cutoff carried by said movable member and arranged for movement with said member into and out of feeding position with respect to the other parts of said feed mechanism.
2. In a feed mechanism for button attaching machines, a raceway, and a movable unitary structure forming a part of said feed mechanism and comprising a lateral guide for a portion of said raceway and a cutoff.
3. In a feed mechanism for button attaching machines, a tack raceway, a movable member forming a part of said raceway, a tack cutoff carried by said movable member and movable therewith, and means arranged between and connected with said movable member and cutoff and movable bodily with these parts for imparting motion to said cutoff relative to said movable member.
4. In a feed mechanism for button attach-

ing machines, a tack raceway, a movable member forming a part of said raceway and pivoted for movement with respect thereto whereby it may be moved out of raceway forming position for the purpose of clearing the raceway, and a tack cutoff pivotally mounted on said movable member and movable with said member about its pivot.

5. In a feed mechanism for button attaching machines, a tack raceway, a movable member forming lateral guide means for a part of said raceway, a tack cutoff pivotally carried by and movable with said member, and means for imparting tack feeding movement to said cutoff when said cutoff is in tack feeding position but disconnected from said cutoff when the cutoff is moved out of tack feeding position.

6. In a feed mechanism for button attaching machines, a tack raceway having a movable portion forming a lateral guide for a portion thereof, a tack cutoff pivotally mounted on said movable portion and capable of tack feeding movement with respect thereto, means for imparting tack feeding movement to said cutoff, and a separable connection between said means and cutoff whereby said movable portion may be moved independently of said means.

7. In a feed mechanism for button attaching machines, a tack raceway, a member forming a part of said raceway and pivoted for movement with respect thereto, a tack cutoff carried by said member, means comprising a link and lever mechanism for imparting tack feeding movement to said cutoff and including a separable connection between said link and cutoff whereby said cutoff is moved in one direction, and resilient means interposed between said cutoff and said pivoted member for imparting motion to said cutoff in the opposite direction.

8. In a feed mechanism for button attaching machines, a tack raceway including a member forming a lateral guide for a por-

tion of the raceway and pivoted for movement with respect thereto, a tack cutoff pivotally carried by said member and movable therewith, means for maintaining said movable member in raceway forming position 50 said means arranged to permit movement of said member out of raceway forming position, and means for imparting tack feeding movement to said tack cutoff when said member is in raceway forming position but disconnected therefrom to permit movement of said member out of raceway forming position.

9. In a feed mechanism for button attaching machines, a tack raceway, a member forming a part of said raceway and pivoted for movement with respect thereto, a tack cutoff pivotally mounted on said member, means for maintaining said member in raceway forming position but arranged to 60 permit movement of said member out of raceway forming position, and means for imparting tack feeding movement to said tack cutoff including a link and lever mechanism, a pin carried by said cutoff and a pin carried by said link said pins arranged for inter-engagement when said member is in raceway forming position but capable of disengagement when said member is moved out of raceway forming position, whereby 65 when said member is in raceway forming position tack feeding movement may be imparted to said cutoff in one direction, and resilient means interposed between said cutoff and member whereby tack feeding movement may be imparted to said cutoff in the opposite direction.

In testimony whereof I have hereunto set my hand this 27 day of August, A. D. 1923.

CHAS. E. PARSONS.
